UNITED STATES PATENT OFFICE

132,947

DESIGN FOR AN INSTRUCTIONAL TABLE

Marjorie Ann Banks, Piedmont, Mo.

Application December 26, 1941, Serial No. 104,869

Term of patent 14 years

To all whom it may concern:

Be it known that I, Marjorie Ann Banks, a citizen of the United States, residing at Piedmont, in the county of Wayne and State of Missouri, have invented a new, original, and ornamental Design for an Instructional Table, of which the following is a specification, reference being had to the accompanying drawing, forming part thereof.

Figure 1 is a perspective view of an instructional table, looking at one end thereof, and showing my new design; and

I claim:

The ornamental design for an instructional table, as shown.

MARJORIE ANN BANKS.
